UNITED STATES PATENT OFFICE.

HUGO A. BUCCINI, OF PHILADELPHIA, PENNSYLVANIA, ASSIGNOR TO VICTORY LAMP COMPANY, OF PHILADELPHIA, PENNSYLVANIA.

COMBINED LIGHTING FIXTURE AND MAIL BOX.

Application filed August 31, 1927. Serial No. 216,536.

This invention relates to improvements in exterior fixtures and more particularly to a combined exterior electric lighting fixture and mail-box.

Among the principal objects of this invention is the provision of a combined exterior electric lighting fixture and mail-box wherein are provided separate compartments constituting respectively a housing for an electric light and a depository for mail.

Another object of the invention is the provision of a device which is so designed as to constitute a lighting fixture for illuminating purposes at the same time that it is adapted for use as a mail-box.

A still further object of the invention is the provision of a combined exterior lighting fixture and mail-box wherein means are provided for facilitating the removal of mail from one compartment thereof as well as for facilitating the insertion or removal of the electric light and its socket from another compartment thereof.

A still further object of the invention is to provide a device which is capable of carrying out the above stated objects and which is as compact, neat and ornamental in appearance as it is simple and inexpensive to manufacture.

Other objects will appear more fully hereinafter.

The invention consists substantially in the combination, construction, location and relative arrangement of parts all as will be more fully hereinafter set forth, as shown in the accompanying drawings, and finally pointed out in the appended claims. For purposes of illustration, a preferred embodiment of the invention has been illustrated in said accompanying drawings, it being understood, of course, that various changes may be made from time to time without departing from the principles of the invention.

In said drawings:

Figure 1 is a front elevational view of the combined exterior lighting fixture and mail-box;

Figure 2 is a side view thereof showing the door through which access is had to the light and mail compartments;

Figure 3 is a central vertical section taken on the line 3-3 of Figure 1; and

Figure 4 is a perspective view of the mounting element for the lamp.

Referring more particularly to the draw-

ings, it will be seen that there has been provided a casing, indicated generally by the reference numeral 10, arranged to be mounted in any desired position by means of the back wall 11 thereof. With the exception 60 of this back wall 11 and the top and bottom walls of the casing, the remaining walls thereof, that is the side and front walls, are provided with openings covered by glass or other such material, as will be explained 65 in greater detail hereinafter. As appears most clearly in Figure 3, the top wall 12 of the casing is inclined downwardly and forwardly and is provided with a transversely extending slot 13 in the upper portion 70 thereof. The forward edge of this inclined top wall 12 is provided with a depending flange 14, while the side edges thereof are provided with the depending flanges 15 constituting the upper portions of the side walls 75 of the casing.

As appears most clearly in Figure 2, the bottom edge of the side flanges 15 and the bottom edge of the front flange 14 lie in substantially the same horizontal plane. The 80 side and front edges of the bottom wall 16 of the casing are formed with upwardly and inwardly extending portions 17 terminating in the vertically extending flanges 18. Completing the frames of the side and front walls 85 of the casing are the vertically extending corner members 19. A horizontally extending member 20 constitutes a tie between the front corner members 19 while a vertically extending member 21 constitutes a tie between the 90 flanges 15 and 18 on one side of the casing. It will thus be seen that the casing constructed as described above is provided with a pair of transversely extending openings in the front wall thereof and with a pair of 95 vertically extending openings in one of the side walls thereof, the opposite side wall being entirely open from front to back.

Secured within these transversely and vertically extending openings, preferably by 100 means of the clip members 22, are a plurality of glass or other transparent or translucent members 23, 24, 25 and 26. Preferably the glasses 23, 24 and 25 are translucent, while the glass 26 is transparent. If desired, the number of the house where the fixture is used, for example 1927, may be painted or otherwise applied upon the upper glass 23 in the front wall of the casing.

Hinged to the back wall 11 of the casing,

as at 27, is a door, indicated generally by the reference numeral 28. This door is provided with the glasses 29 and 30, the latter being preferably transparent and arranged 5 opposite the other transparent glass 26. A hook 31, or a similar fastening device, is provided at the free edge of the door 28, for securing the same in closed position.

Depending from the top wall 12 of the 10 casing is a transversely extending flange 32, the lower edge of which is provided with a horizontally extending groove 33. Preferably this depending flange 32 lies in the plane separating the side wall glasses 25 and 26. Secured to the bottom wall 16 of the casing is a substantially inverted U-shaped member 34 having the oppositely extending branches 35. Screws 36 pass through these branches 35 and through the 20 bottom wall 16 into threaded engagement with the nuts 37. The rear edge of this U-shaped member 34 is provided with a transversely extending upwardly presenting groove or channel 38, said groove lying in substantially the same vertical plane as the 25 similar but downwardly presenting groove 33. The member 34 is further provided with an opening 39 in the base wall thereof, this opening being arranged to receive a lamp 30 socket 40 for a lamp 41, preferably an electric lamp. An opening 42 is preferably provided in the back wall 11 of the casing through which the electric wires leading to said socket may pass.

35 Arranged to be slipped into the casing with the upper and lower edges thereof respectively received within the upper and lower grooves or channels 33 and 38 is an opaque partition member 43, preferably of metal. When this member 43 is inserted in position, as most clearly appears in Figure 3, the casing is divided into two compartments, one arranged in advance of the other, the forward compartment constituting a housing 40 for the lamp 41 and the rear compartment constituting a depository for any mail or similar matter which may be inserted through the transversely extending slot 13 provided in the upper wall 12 of the casing. 45 The provision of this removable partition member 43 facilitates the removal of any mail or other matter from the rear compartment, while at the same time it facilitates the removal or replacement of the lamp 41 or its socket 40 whenever the latter is necessary. An important feature of this partition member 43 is that, by reason of its opaqueness, it serves to conceal the fact that the mail-box is other than merely an exterior lighting fixture, this being especially true when the lamp 41 is turned on at night. Still further, this opaque partition member constitutes in effect a diffuser for the light and consequently increases the general effectiveness of the 55 device as an illuminating fixture. The trans-

parent glass 26 in the one wall of the casing and the similar glass 30 in the door of the casing makes the interior of the mail compartment readily visible without the necessity of opening the side door.

In order to protect the interior of the mail compartment from the elements, the casing is provided with a cover 44 hinged, as at 45, and adapted to overlie the mail slot 13. Preferably this cover 44 is provided with 75 side portions 46 overlying the upper portions 15 of the side walls of the casing, thereby providing a neat and finished appearance to the upper portion thereof.

In order to still further enhance the appearance of the combined exterior light fixture and mail-box, the latter is provided with the cross rods 47 upon one side and the front wall of the casing as well as upon the hinged door 28. If desired, a spring 85 metal clip 48 may be secured to the under surface of the casing for receiving mail of a more or less bulky nature, such as magazines, newspapers and the like.

90 It is to be understood, of course, that various changes may be made in the construction of the invention herein disclosed without departing from the spirit or principles thereof, and it is accordingly intended to claim the invention broadly as well as specifically as indicated in the appended claims.

95 What is claimed as new and useful is:—

1. In a combined exterior lighting fixture and mail-box, a main casing, a transversely extending removable partition in said casing arranged to divide said casing into a pair of compartments constituting, respectively, a housing for a lamp and a depository for mail, and a door hinged to said casing through which access is had to both of said 100 compartments.

105 2. In a combined exterior lighting fixture and mail-box, a main casing having an opening in one side thereof, a member depending from the top of said casing, the lower edge 110 of said member having a transversely extending downwardly presenting channel, a second member secured to the bottom of said casing, said latter member being provided with an upwardly presenting channel lying 115 in the transverse plane of said downwardly presenting channel, and a removable partition member arranged to be slidably received within said channels.

120 3. In a combined exterior lighting fixture and mail-box, a main casing, means arranged to be removably inserted through one side of said casing for dividing the latter into a pair of transversely extending compartments, a supporting member for a lamp secured to the base wall of one of said compartments, and a door hinged to said casing through which access is had to both of said compartments.

125 4. In a mail-box structure, a main casing 130

having a downwardly and forwardly inclined top wall, said wall being provided with a transversely extending slot, a transversely extending member depending from said wall and lying substantially in the vertical plane of one of the edges of said slot, a lamp support secured to the base wall of the casing with one edge thereof also lying in said plane, a pair of transversely extending channels respectively carried by said depending member and said supports, and a partition arranged to be slidably received within said channels, said partition serving to divide said casing into separate compartments constituting, respectively, a housing for the lamp and a depository for mail inserted through said slot.

5. In a mail-box structure, a main casing, one side wall of said casing being open and the opposite side wall thereof being fitted with a transparent glass of a width less than that of said wall, a door hinged to said cas-

ing and arranged to close said open side wall, said door being also fitted with a transparent glass of a width substantially equal 25 to that of said first mentioned glass, and a partition extending across the interior of said casing and lying substantially in the vertical plane of the forward edges of said glasses.

6. In a mail-box structure, a main casing, a removable opaque partition arranged to extend from side to side of said casing whereby to provide a front and a rear compartment, a lamp located within said front 35 compartment, a door hinged to said casing and arranged to close the open sides of both of said compartments, and a pair of transparent glasses in the portions of said door and casing extending rearwardly of said 40 partition,

In testimony whereof, I have hereunto affixed my signature.

HUGO A. BUCCINI.
